(57) **CLAIM**

The ornamental design for the hose clamp, as shown and described.

DESCRIPTION

FIG. 1 is a perspective view of the hose clamp showing my new design;

FIG. 2 is a rear view thereof;

FIG. 3 is a front view thereof;

FIG. 4 is a top plan view thereof;

FIG. 5 is a bottom plan view thereof;

FIG. 6 is a left side view thereof;

FIG. 7 is a right side view thereof;

FIG. 8 is a perspective view thereof in a state of use;

FIG. 9 is a fragmentary enlarged view of the clasp structure of the hose clamp seen at the tops of FIGS. 1 and 2. The hook end and a portion of the arm that forms the lock mechanism has been removed for clarity of illustration; and,

FIG. 10 is a perspective view of the opposite side of FIG. 9. The broken lines in the FIG. 8 view depict environmental structure that forms no part of the claimed design.
